UNITED STATES PATENT OFFICE.

ERNEST BUSSEY, OF DOTHAN, ALABAMA, ASSIGNOR TO FOOT AIR ACCELERATOR COMPANY, OF CINCINNATI, OHIO, A CORPORATION OF ALABAMA.

FOOT AIR-ACCELERATOR FOR HYDROCARBON-MOTORS.

1,218,927.

Specification of Letters Patent.

Patented Mar. 13, 1917.

Application filed June 29, 1916. Serial No. 106,718.

To all whom it may concern:

Be it known that I, ERNEST BUSSEY, a citizen of the United States, and resident of Dothan, county of Houston, State of Alabama, have invented certain new and useful Improvements in Foot Air-Accelerators for Hydrocarbon-Motors, of which the following is a specification.

This invention relates to an air accelerator for internal combustion engines. The objects of the invention are to provide a simple air valve which may be attached to the intake manifold of an internal combustion engine between the carburetor and the engine; to provide easily attached and adjustable connections so that the valve may be operated from a foot pedal; to provide a valve all the parts of which are inclosed and thus protected from dirt, grit, etc.; to provide means for furnishing the intake of the valve with heated air; and to provide a valve which may be manufactured for a small amount of money. These and other features of the invention will be described 25 in connection with the drawings and pointed out in the appended claims.

In the drawings, in which like reference characters indicate the same part in the different views,

30 Figure 1 is a perspective view showing the location of the valve and the arrangement of the operating connections to the same.

Fig. 2 is a longitudinal sectional view 35 through the valve.

As clearly shown in the drawings the valve is adapted to be attached to the intake manifold of the engine in an automobile, and operated by a foot pedal which may extend through the foot board of the machine and is connected to the valve in any suitable manner. The valve is actuated to admit air to the intake manifold to accelerate the speed of the engine when desirable. If 45 the carburetor is set so that the engine will operate properly at low speeds, the mixture at higher speeds is richer than necessary. Consequently, if air is admitted, the engine will speed up, operating more satisfactorily and using less gasoline. With the spark and gas levers of the engine at a certain setting, opening the air accelerator valve will cause the engine to speed up to a certain higher speed, but any further opening 50 of the air valve will dilute the mixture too

much and the engine will then operate improperly. Hence the air valve may be used to accelerate the speed of the engine to a certain amount which may be called the critical speed. For example, if the automobile is running at the rate of fifteen miles 60 an hour, the foot air valve might increase the speed to twenty miles an hour.

The valve comprises a body portion 10 which is reduced at one end to provide a 65 threaded nipple 11, whereby the valve is attached to the intake manifold of the engine. The other end of the body 10 is cylindrical forming a boss 12 which is enlarged as at 13, thereby forming a shoulder 14. The enlarged portion 13 is threaded and adapted to receive the hollow cap 15, so that the outer surface of the cap and main part of the body are flush. The body part 10 is formed with a bore 16 and a counter-bore 70 17 at the nipple end. The counter-bore forms an air chamber, and is furnished with an opening 18 through the side of the body. At the nipple end, the counter-bore is formed with a bevel seat 19, and a valve 20 75 is adapted to close this end of the counter-bore or air chamber, and cooperates with the seat 19 for this purpose. The stem 21 of the valve extends through the air chamber 17 and slidably fits the bore 16. The 80 end is threaded, as at 22, and a nut 24 and lock nut 23 mounted on the same. A spring 25 is interposed between the nut 24 and the shoulder 14, to thereby hold the valve to its seat. The nut 24 may be provided with 85 an annular groove 26 in its face to form a seat for the end of the spring. The maximum suction or reduction of pressure in the intake manifold occurs when the throttle valve is substantially closed. As the 90 valve is opened the suction is less. The spring 25 is of such strength that the valve will be held to its seat against the greatest suction that may obtain in the intake manifold. The pressure exerted by the spring 100 25 may be adjusted by manipulating the nuts 23 and 24.

The spring, nuts and end of valve stem are adapted to be inclosed by a cap or housing 105 15. The housing is formed with a slot 27 adjacent the nuts 23 and 24 and with an apertured ear 28 on each side of the same. A pin 29 is secured in the apertures of the ears in any suitable manner and is adapted to pivotally support a bent lever 30. One 110

arm of the lever is bent to act on the end of the valve stem, the other arm extending substantially parallel to the wall of the cap, and is apertured at its end to have fastened thereto in any suitable manner a rod or link 31. The link is bent to pass around the cap 31 and has its other end forked as at 32, and is furnished with a turn buckle 33, whereby it may be adjusted to fit different makes of automobiles. A rod has a straight portion 34 pivotally mounted on the dash by any suitable means as the clips 35. The straight portion has an arm 36 at one end pivotally connected to the fork 32, and at 15 the other end an arm 37 which is bent to extend through the floor board of the automobile and terminates in a foot pad 38. Obviously the above described means for operating the valve from the floor board adjacent the operator of the automobile 20 may be varied.

The opening 18 to the air chamber 17 may have a hot air pipe 39 mounted therein, and 25 extending to the exhaust pipe or other region of hot air, to thereby furnish heated air for the valve. The pipe may be of any suitable shape and material.

From the above description it will be obvious that when the foot pad is pushed 30 downward, the lever 30 will be moved to act on the end of stem 21 and open the valve,

in proportion to the extent of movement of the foot pad. The spring 25 will return the parts to their normal or closed position.

Thus it will be apparent that a very efficient and easily operated means has been provided for quickly accelerating the speed of an automobile engine. Although a preferred form of the invention has been described, it is obvious that many of the parts 40 may be varied without departing from the spirit of the invention.

Having described the invention what is claimed is:

An air valve adapted to be attached to 45 the inlet manifold of an internal combustion engine comprising a body formed with an air chamber open at one end thereof and having an air inlet, a nipple at said end for attaching the valve to the inlet manifold, 50 said nipple formed with a valve seat, a valve coöperating with said seat and having a stem extending through the body and projecting beyond the same, spring means to close the valve against the difference of 55 pressure in the chamber and manifold, a cylindrical cap carried by the body and inclosing said spring and stem and carrying means coöperating with the stem for actuating the valve.

In testimony whereof I affix my signature.

ERNEST BUSSEY.
